UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

SPEED-REGULATOR FOR TALKING-MACHINES.

1,321,179.

Specification of Letters Patent. Patented Nov. 11, 1919.

Application filed February 1, 1917. Serial No. 145,889.

To all whom it may concern:

Be it known that I, JOSEPH WOLFF, a subject of the King of Great Britain and Ireland, residing in the borough of Brooklyn, county of Kings, State of New York, have invented a certain new and useful Speed-Regulator for Talking-Machines, of which the following is a specification.

My invention relates to devices for regulating the speed of talking machine motors, and has for its object to provide a device which will be simple and cheap of construction, which will not get out of order, and wherein the parts will always be in coöperative relation with each other.

This and further objects will more fully appear in the following specification and accompanying drawings considered together or separately.

20 In the drawings,—

Figure 1 is a side elevation of the operative parts of a disk record talking machine provided with my invention; and

25 Fig. 2 is a top plan view of the brake beam lever.

Fig. 3 is a detail sectional view.

In all of the above views, like parts are designated by the same reference characters.

30 In carrying out my invention, I provide a casing 1 having a motor board 2, to the under side of which a motor 3 is secured. The main shaft 4 of the motor extends upward through the motor board, and carries thereon a turn-table 5 on which a disk record

35 6 is adapted to rest. The motor illustrated is the usual spring motor having a spring barrel 7 which is geared to the main shaft 4, as is common.

A governor shaft 8 is carried in suitable 40 bearings on the motor frame, and is driven from a worm wheel (not shown) on the main shaft, which meshes with a worm 9 on the shaft 8. A disk 10 is carried by the shaft, but the shaft is free to rotate in the disk.

45 A collar 11 is secured to the shaft 8 and spring arms 12 connect the collar and disk. A weight 13 is carried by each arm 12.

Pivoted to the motor frame is a brake beam 14 which carries a brake shoe 15 adapted to engage the disk and retard the motor. 50 A lever 16 extends from the brake beam, and the extremity of the lever is provided with a slot 17, with which a pin 18 engages. The pin is carried by or integral with a plug 19 which carries a lug 20, projecting from

the side thereof and adapted to engage a spiral slot in a sleeve 20a rotatably mounted in a tubular bearing 21 fitted in the motor board. The sleeve is rotated by a crank 22 fixed to its upper end on the upper side of the motor board to thereby effect an up and down reciprocatory movement of the plug and its pin, by means of the engagement of the spiral slot and lug. The crank carries a pointer 23 which coöperates with a scale on the motor board, and by means of which the brake shoe may be set to cause the motor to travel at the desired speed. The lug 20 also engages a straight slot 24 in the tubular bearing 21 and prevents rotation of the plug 19 and guides the same in its up and down movements. A spring 25 tends to release the brake shoe from the disk. The pin 18 is made of sufficient length to extend a considerable distance beyond the brake lever 16 so as to always remain in engagement with the slot 17 in the brake lever. Of course, if desired, a nut or other projection may be added to the end of the pin 18, but this is not essential as the pin is of such length that it cannot become disengaged from the slot 17.

The operation of the device is obvious. The pin 18 is of such a length that no matter what the position of the lever 16, the pin 85 will always be in engagement with the slot 17. This will prevent dislocation of the lever from the indicating mechanism caused by vibrations in the motor.

In accordance with the provisions of the 90 patent statute, I have described the principle of my invention together with the apparatus which I now consider to represent the best embodiment thereof, but I desire to have it understood that the apparatus shown 95 is merely illustrative and that the invention can be carried out in other ways.

Having now described my invention, what I claim and desire to secure by Letters Patent is:

1. In a speed regulator for talking machines and the like, a cabinet, a motor and a frame therefor mounted in the cabinet, a brake disk operated by said motor, a brake beam pivoted to the motor frame and provided with a brake shoe adapted to engage said disk, a lever fixed to and projecting from the brake beam and provided with an elongated slot at its free end, a rotatable sleeve having a spiral slot mounted in said 105 110

cabinet, a plug loosely fitted in said sleeve and provided with a lug adapted to engage said spiral slot and having a pin-like projection at its lower end adapted to engage 5 and pass through the slot in said lever and projecting a considerable distance beyond said lever, and means for rotating said sleeve in opposite directions to move said plug upwardly or downwardly to thereby adjust 10 the brake shoe with relation to the brake disk.

2. In a speed regulator for talking machines and the like, a motor board, a motor and a frame therefor mounted on said motor board, a brake disk operated by said motor, a brake beam pivoted to the motor frame and provided with a brake shoe adapted to engage said brake disk, a lever fixed to and projecting from the brake beam and provided with an elongated slot at its free end, a rotatable sleeve provided with a spiral slot near its lower end mounted in the motor board, a plug loosely fitted in said sleeve and provided with a side lug adapted to engage said spiral slot and having a pin-like projection at its lower end adapted to engage and pass through the elongated slot in said lever and extending considerable distance beyond said lever, and means for rotating said sleeve in opposite directions to move said plug upwardly or downwardly to thereby adjust the brake shoe with relation to the brake disk.

3. In a speed regulator for talking machines and the like, a motor board, a motor and a frame therefor mounted on said board, a brake disk operated by said motor, a brake beam pivoted to the motor frame and provided with a brake shoe adapted to engage 35 said brake disk, a lever fixed to and projecting from the brake beam and provided with an elongated slot at its free end, a rotatable sleeve provided with a spiral slot near its lower end mounted in the motor board, a plug loosely fitted in said sleeve and provided with a side lug adapted to engage said spiral slot and having a pin-like projection at its lower end adapted to engage and pass through the elongated slot 50 in said lever and extending considerable distance beyond said lever, means for rotating said sleeve in opposite directions to move the plug upwardly or downwardly to thereby adjust the brake shoe with relation to the 55 brake disk, and a spring for normally disengaging the brake shoe from the brake disk and holding said lever in engagement with the lug.

4. In a speed regulator for talking ma-

chines and the like, a motor board, a motor 60 and a frame therefor fixed to said board, a brake disk operated by said motor, a brake beam pivoted to the motor frame and provided with a brake shoe to engage said 65 brake disk, a lever fixed to and projecting from the brake beam and provided with an elongated slot at its free end, a tubular bearing fixed in the motor board, a rotatable sleeve provided with a spiral slot near its lower end fitted in said tubular bearing, a 70 plug loosely fitted in said sleeve and provided with a side lug adapted to engage said spiral slot and having a pin-like projection at its lower end adapted to engage and pass through the elongated slot in said lever and 75 extending considerable distance beyond said lever, and means for rotating said sleeve in opposite directions to move said plug upwardly or downwardly to thereby adjust 80 the brake shoe with relation to the brake disk.

5. In a speed regulator for talking machines and the like, a motor board, a motor and a frame therefor fixed to said board, a brake disk operated by the motor, a brake 85 beam pivoted to the motor frame and provided with a brake shoe to engage said brake disk, a lever fixed to and projecting from said brake beam and provided with an elongated slot at its free end, a tubular bearing fixed in the motor board and having a longitudinal slot in its lower end, a rotatable sleeve mounted in said tubular bearing and having a spiral slot near its lower end adjacent to the slot in the tubular bearing, a 90 plug loosely fitted in said sleeve and provided with a side lug adapted to engage the spiral slot in said sleeve and extending into the slot in the tubular bearing, said plug also having a pin-like projection at its lower end adapted to engage and pass through the elongated slot in said lever and extending considerable distance beyond said lever, and means for rotating said sleeve in 95 opposite directions to move the plug upwardly or downwardly to thereby adjust the brake shoe with relation to the brake disk, the engagement of said side lug with the longitudinal slot in the tubular bearing serving 100 to prevent rotation of the plug and guiding 105 it in its movements.

This specification signed and witnessed this 27th day of January, 1917.

JOSEPH WOLFF.
